Inventor

Edward W. Brower

By his Attorneys

Edgar Dickey

UNITED STATES PATENT OFFICE.

EDWARD W. BROWER, OF FLUSHING, NEW YORK.

TABLE FOR COMPUTING EXCESS-BAGGAGE RATES.

Application filed April 25, 1922. Serial No. 556,450.

To all whom it may concern:

Be it known that I, EDWARD W. BROWER, a citizen of the United States, and residing at Flushing, Long Island, in the county of 5 Queens and State of New York, have invented certain new and useful Improvements in Tables for Computing Excess-Baggage Rates, of which the following is a specification, such as will enable those skilled in the 10 art to which it appertains to make and use the same.

This invention relates to a table or chart for use in computing excess baggage rates and is designed particularly for use by 15 those handling baggage to be checked and shipped from one point to another by railroads who allow the shipment of a predetermined weight of baggage for each individual free and without charge but, in the 20 event of excess weight of the baggage of an individual a charge is made by the railroad; and the object of my invention is to provide a table or chart which is to be used by those employed by the railroad for handling such 25 baggage whereby the charges for excess baggage may be instantly and accurately determined without the necessity of mathematical calculations by such employee; and with this and other objects in view the invention 30 consists in a table or chart of the class and for the purpose specified which is simple in construction and efficient in use, and which is constructed and arranged as hereinafter set out.

35 The invention is fully disclosed in the following specification, of which the accompanying drawing forms a part, said drawing being a plan view of a table or chart with part of the data arranged thereon.

40 In the drawing I have shown, for illustrating one use of my invention, a table or chart 1 which may be composed of a sheet of paper, canvas or the like, or may be composed of cardboard or other suitable material 45 and, in practice, this chart is divided into twenty vertical columns 2 by vertical lines 3 and into a multiplicity of horizontal rows 4 by horizontal lines 5. The columns 2 are provided at the top thereof and approximately centrally thereof with the numerals 50 one to twenty dollars (\$1 to \$20) reading from left to right as shown at 6, and the horizontal rows are divided into nineteen sections designated by the numerals 5, 10, 15 and 20, etc. up to 95, said numerals being

located at the opposite sides of the table or chart and centrally thereof as shown at 7.

The vertical columns and horizontal rows 2 and 4, or the lines 3 and 5 forming such columns, form a multiplicity of numeral 55 spaces 8 in each of which is placed one or two sets of numerals, one set of numerals being located at the left of the spaces 8 as indicated at 9 and the other set being located at the right of such spaces as indicated at 10. In some instances, some of these spaces will be left blank and in other instances but one set of the numerals will be applied, as is apparent on a consideration of the drawing.

In the accompanying drawing, I have shown only a predetermined number of the numerals for the purpose of illustrating the use of my improved table or chart, but it will be understood, in practice, that all of 70 the numeral spaces 8 or the majority thereof will have the numerals 9 and 10 therein and, in practice, the set 9 of numerals will be applied in black or blue ink to the chart, while the set of numerals 10 will be applied in 75 preferably red ink in order to distinguish from the set of numerals 9.

The numerals 5, 10, 15, etc. to 95 represent pounds or, in other words, the excess 80 pounds of baggage on which the rates are to be computed. The numerals \$1.00 to \$20.00 represents the excess baggage rates in dollars per hundred. The set of numerals 9 in the spaces 8 represents the excess baggage 85 rates in cents while the set of numerals 10 in the spaces 8 represents the amount to be collected and as heretofore set out will be 90 preferably characterized by the use of red ink.

In the use of the chart and in computing 95 a given charge to be collected for a predetermined amount of excess baggage in pounds, the rate is first determined by the collector in the usual manner and by consulting a rate book if the same is necessary. The rate charged is governed by the distance to be traveled, in other words, baggage sent from New York to San Francisco 100 will be charged at a greater rate and possibly twenty dollars for a hundred pounds, 105 while baggage from New York to Boston may be charged at a rate of possibly a dollar per hundred pounds. The collector will then trace down the vertical column 2 designated by the rate per hundred to be charged 110

to a horizontal column or a section of columns designed by the excess pound or pounds of the baggage, as for example let us presume that we have a case of five 5 pounds excess baggage which is to be charged for at the rate of \$8.47 per hundred pounds. We first go to the vertical column headed by the numerals \$8.00 and trace down to the horizontal row designated by 10 the numeral 5 representing pounds in the space 8, we find in the set of numerals 10 forty cents, this would be the amount to be collected at the rate of \$8 per one hundred pounds. In order to fix the rate at 15 forty-seven cents, we trace through the horizontal row under five pound or designated by the numeral 5 and find by examining the set of numerals 9 in which 45 to 60 are shown there is a rate charge of three cents 20 which appears in the set of numerals 10 in such spaces, in other words, the amount to be collected will be forty-three cents for the above example.

It will be apparent that in the horizontal 25 columns or in the spaces 10 formed thereby and reading from left to right, the set of numerals 9 read from 5 to 95 and in some instances read from 1 to 96, 3 to 98, etc. It will be apparent on an examination of the 30 chart as shown and, as previously stated, these sets of numerals 9 are used in computing the cents charges if the rate per hundred pounds involves cents as per the example \$8.47, and in the above example it will be 35 noted that five pounds of excess baggage at the rate of \$8.47 per hundred pounds there will be a charge to be collected of forty-three cents by the collector.

In order that the use of the table or chart 40 may be clearly understood, we submit the following additional example, in which case we have fifty-five pounds of excess baggage at the rate of ninety-seven cents per hundred pounds, the rate to be collected is 45 fixed by tracing through the third horizontal row in the sections 7 designated by the numeral 55 to the last vertical column in which we find in the set of numerals 9, ninety-seven cents to the right of which, or 50 in the set of numerals 10 we find the numeral 54 cents this would be the amount to be collected in this example, in other words, fifty-five pounds at the rate of ninety-seven cents per hundred there will be 55 a charge of fifty-four cents to be collected by the collector.

It will also be apparent that if the rate 60 of one hundred pounds is in even dollars, as per example, fifty-five pounds at a dollar a hundred, the charge will be fifty-five cents, and there will be no need for considering the set of numerals 9, as another example, if the rate was twenty dollars per hundred pounds for fifty-five pounds of excess baggage the charge would be eleven dollars and, in this 65

connection, I call attention to the fact that the numerals in the top column of section 7 will all be in red ink and will designate dollars and cents, as per example, eleven dollars as above set out, and this is also true of all 70 of the separate sections 7 and considering the top horizontal row designated by the numeral 5 we will find under the vertical column headed by the numerals \$20.00, \$1.00.

It will be apparent that I am not necessarily limited to any specific use of my improved table or chart, nor am I limited to the specific arrangement of the columns, as herein set out, and various changes in and modifications of the chart herein shown and described may be made, within the scope of the appended claims, without departing from the spirit of my invention or sacrificing its advantages.

Having fully described my invention, 85 what I claim as new and desire to secure by Letters Patent, is:—

1. An excess baggage rate computing table 90 of the class described comprising numerically designated horizontal rows and vertical columns, the vertical columns being designated by numerals representing the rates per hundred pounds, the horizontal rows being designated by numerals five to 95 ninety-five inclusive denoting the excess weight of baggage, and the spaces formed by said vertical columns and horizontal rows being provided with numerals denoting the amount to be collected.

2. An excess baggage rate computing table 100 of the class described comprising numerically designated horizontal rows and vertical columns, the vertical columns being designated by numerals representing the rates per hundred pounds, the horizontal 105 rows being designated by numerals five to ninety-five inclusive denoting the excess weight of baggage, and the spaces formed by said vertical columns and horizontal rows being provided with numerals denoting the amount to be collected and with other numerals designating the cent rate charges per hundred pounds.

3. An excess baggage rate computing table 115 of the class described comprising numerically designated horizontal rows and vertical columns, the vertical columns being designated by numerals representing the rate per hundred pounds, the horizontal rows being designated by numerals denoting the excess weight of baggage, and the spaces formed by the vertical columns and horizontal rows being provided with numerals denoting the amount to be collected.

4. An excess baggage rate computing table 125 of the class described comprising numerically designated horizontal rows and vertical columns, the vertical columns being designated by numerals representing the rate per hundred pounds, the horizontal rows being 130

designated by numerals denoting the excess weight of baggage, the spaces formed by the vertical columns and horizontal rows being provided with numerals denoting the amount to be collected and with other numerals designating the cent rate charge per one hundred pounds, and means for dis-

tinguishing the last named numerals in said spaces from each other.

In testimony that I claim the foregoing ¹⁰ as my invention I have signed my name this 22nd day of April, 1922.

EDWARD W. BROWER.
